UNITED STATES PATENT OFFICE

147,476

DESIGN FOR A RING

Harry L. Shainfeld, Los Angeles, Calif.

Application July 20, 1946, Serial No. 131,761

Term of patent 3½ years

(Cl. D45—10)

To all whom it may concern:

Be it known that I, Harry L. Shainfeld, a citizen of the United States, residing at Los Angeles, in the county of Los Angeles and State of California, have invented a new, original, and ornamental Design for a Ring, of which the following is a specification, reference being had to the accompanying drawing, forming part thereof.

I claim:

The ornamental design for a ring, as shown.

HARRY L. SHAINFELD.
